ATTORNEYS

there is shown a further modification of the invention, wherein the head 24 has formed therewith the reversely inclined steps or pedals 25, and 26, respectively, thus permitting use thereof when either inside of the tub or outside thereof, as should be clearly obvious, and the soap holder slab 27 is innermost of the tub, which is apparent.

What is claimed is:

1. A fitting for a bath tub, comprising a post for anchorage next to the tub and rising vertically thereto, a head at the uppermost end of the post and bridging the walling of the said tub, a foot step formed with the head and having drainage into the tub, a soap holder built with the head and exposed within the said tub, a base for the post and fasteners engaging the base, the step being inclined in a determined direction and having a cavity conforming to a person's foot.

2. A fitting for a bath tub, comprising a post for anchorage next to the tub and rising vertically thereto, a head at the uppermost end of the post and bridging the walling of the said tub, a pair of foot steps formed in said head each having a drainage passage formed therein and adapted to empty into the tub, one of said foot steps being

inclined inwardly to said tub and the other inclined outwardly from said tub.

3. A fitting for a bath tub, comprising a post for anchorage next to the tub and rising vertically thereto, a head at the uppermost end of the post and bridging the walling of the said tub, a pair of foot steps formed in said head each having a drainage passage formed therein and adapted to empty into the tub, one of said foot steps being inclined inwardly to said tub and the other inclined outwardly from said tub and each of the said steps having a cavity formed therein for the reception of a person's foot.

NED CLARK.
